AUTOMATIC REMOTELY CONTROLLED FIRE EXTINGUISHER

Clarence Noel Cahusac, Newark, N. J., assignor to
C-O-Two Fire Equipment Co., Newark, N. J., a
corporation of Delaware

Application June 5, 1947, Serial No. 752,759

13 Claims. (Cl. 169—26)

1

The present invention relates generally to fire extinguishers and more particularly to discharge mechanism for containers, cylinders or tanks holding fluid under pressure, such for example as carbon dioxide.

One object of the invention is to provide novel and improved means comprising a heat actuated device or temperature responsive device and a valve controlled thereby for automatically releasing the fluid from the container upon a certain increase in temperature in the vicinity of said heat actuated device.

Another object is to provide apparatus of this character which shall include novel and improved means whereby said valve can be automatically operated at the space to be protected or at a point remote therefrom.

Still another object is to provide a novel and improved fire detecting unit which shall be quickly and positively responsive to temperature rises and which can be easily and quickly applied to a fire extinguisher.

A further object is to provide in a fire extinguisher having a valve operating mechanism of the squeeze-grip type, a novel and improved heat-actuated means for automatically controlling actuation of said valve operating mechanism to open the valve and release the fire extinguishing fluid.

Other objects and advantages of the invention will be apparent from the description thereof to follow taken in connection with the accompanying drawings, in which

Figure 1 is a side view of a fire extinguisher embodying one form of my invention, the valve being shown in normal closed position and parts being shown in section.

Figure 2 is a similar view but showing the valve in open position.

Figure 3 is a fragmentary top plan view thereof.

Figure 4 is a side view of a fire extinguisher embodying a modified form of the invention, the valve being shown in normal closed position and parts being shown in section.

Figure 5 is a side view of a fire extinguisher embodying still another modified form of the invention, the valve being shown in normal closed position and parts being shown in section.

Figures 6 and 7 are views similar to Figure 5 but each showing a further modified form of the invention.

Figure 8 is an enlarged front view of the thermostatic element used with the improved fire extinguishers.

2

Figure 9 is a sectional view taken on the plane of the line 9—9 of Figure 8.

Referring to Figures 1 to 3, inclusive, a cylinder 1 for liquefied carbon dioxide or other highly compressed fluid is shown supported on a side wall 2 by straps 3. An outlet fitting 4 is threaded into the neck of the cylinder in the usual manner.

The fitting has a central vertical delivery passage 5 communicating with a port 6 which extends laterally therefrom and through an internally screw threaded extension 7 on the fitting to the exterior thereof. An elbow sleeve 8 has one end threaded into the extension 7 and its other end connected to a delivery pipe 9. This pipe leads to and is supported on a partition wall 10 by brackets 11 and then passes through an opening 12 in the wall to the other side of said wall to the space to be protected where its free end terminates in a nozzle portion 13. The port 6 serves as a discharge port as well as a port for filling the cylinder.

At its upper end the vertical delivery passage 5 is enlarged to form a seat for a safety disk 14 held in place by a ported baffle or anti-recoil screw plug 15 threaded into said enlarged portion. The safety disk is arranged to rupture at a predetermined pressure so as to prevent the building up of excessive pressure in the cylinder. The anti-recoil member distributes the fluid in equal amounts in opposite directions to prevent recoil upon discharge of fluid upon accidental puncturing of the disk 14.

The fitting is formed with a lateral extension 16 having a port 17 communicating at its inner end with the vertical delivery passage 5, the outer end of said port being enlarged. On its opposite side, the fitting is formed with an enlarged extension 18 and with a chamber 19 communicating at its inner end with the delivery passage 5 and at its outer end with an internally screw threaded recess or chamber 20 formed in the extension 18. The chamber 20 is greater in diameter than the chamber 19 thereby forming a shoulder between them.

Slidably mounted in the chamber 19 is a check valve 21 having a cup-shaped portion 22 at one end with a gasket 23 therein and having a reduced portion at its other end forming a shoulder 24. The valve 21 is actuated by a stem or rod 25 having one end fastened thereto. The stem extends through the port 17 in the extension 16 and projects slightly beyond the outer end of said extension as seen in Figure 1. A sealing gasket 26 is located in the outer enlarged end 55 of port 17 and held by a nut 27 screwed into

said port to prevent the escape of gas around the stem and the walls of the enlarged portion during discharging and recharging of the cylinder, the nut also constituting a close fitting guide for the stem.

An externally screw threaded plug member or nut 28 is threaded into the threaded recess 20 of the extension 18. The nut is formed with a central elongated recess 29 which terminates at the inner end of the nut in an enlarged chamber 30 forming a shoulder 31 on the nut. A stem or rod 32 has one end fastened to the reduced portion 24 of the valve 21 and extends through the chamber 30 into the elongated recess 29, said recess serving as a guide for the stem 32.

The gas from the cylinder which passes through the delivery passage 5 builds up a pressure in the chamber behind the valve thereby forcing the valve into its forward home position, that is, toward the right as viewed in Figure 2 against its seat 33 formed on the inner wall of port 17. The valve blocks the passage of gas from the delivery passage 5 to and through the delivery port 6. A spring 34 surrounds the reduced portion of the valve and the stem 32 and has one end seated against the shoulder 24 on the valve and its other end seated against the shoulder 31 on the nut 28. The spring urges the valve against its seat 33 when no gas pressure is present.

The apparatus for actuating the piston valve automatically comprises a lever 35 provided with a recess 36 at one end. The lever is pivotally connected to the fitting 4 by means of a pivot pin 37 mounted in a perforated enlargement 38 formed at the top of the outer end of the extension 16 and extending through the side walls 39 of the recess 36. The lever is formed with an internal rib or protuberance 40 normally out of engagement with the outer projecting end of the valve stem 25. A plate 41 is positioned along the upper surface of the lever and is fastened thereto by means of bolts 42. The plate extends beyond the outer free end of the lever forming an extension 43 of the lever which is provided with an opening 44. At the inner end of the lever, the plate extends upwardly as at 45 and is provided with a slot 46 at its outer edge.

A pair of vertically disposed straps 47 encircle the extension 18 of the fitting 4 at their lower ends and at their upper ends support one end of a tubular guide member 48. The straps are held in position by bolts 49. Another horizontally disposed strap 50 has one end fastened to the pair of straps about midway their height and is twisted at its other end to form an upward extension 51 formed with an opening 52 for supporting the tubular guide member. An eyelet 53 is inserted in the opening 52 through which the tubular guide member extends.

The fitting 4 is formed adjacent its lower end with a lateral extension 54 and secured to said extension by means of a rivet 55 is an elongated handle member 56. A rod 57 having an enlargement 58 at one end and a screw threaded portion at its other end passes loosely through an opening 59 in the handle member 56 and through the opening 44 in the extension 43 of the lever 35 protruding above the lever. A compression spring 60 surrounds said protruding portion and is interposed between the lever and a wing nut 61 on the outer threaded end of the rod. The spring 60 exercises a greater force than spring 34 and exerts a downward pressure against the extension 43 so that the lever 35 is normally urged

downwardly. The tension of the spring may be adjusted by the wing nut.

When the lever 35 is forced downwardly by the spring 60 its rib portion 40 engages the protruding end of the valve stem 25 and moves said stem inwardly thereby forcing the valve 21 off of its seat 34. Fluid then escapes through the delivery passage 5, the port 6 and into the delivery pipe 9 and through the nozzle 13 where it is sprayed on the fire as indicated at 62.

The apparatus for controlling the movement of the lever 35 and for normally holding said lever against movement consists of the tubular guide member 48 which extends toward the wall 10 and through an opening 63 therein to its other side where it is curved slightly and then extends downwardly along the opposite side of said wall and is supported at its lower end by a horizontally disposed bracket 64 secured to the upper end of a strap 65 which is fastened to the wall by bolts 66. The tubular member may be provided with a sleeve or bushing 67 where it passes through the straps 47 and bracket 64. Slidably mounted in the tubular guide member 48 is a wire 68 which is slightly longer than the guide member. The wire passes outwardly through the end of the horizontal portion of the guide member and its end extends through the slot 46 in the extension 45 of the strap 41 on the lever. An enlargement or head 69 larger than the slot is formed on this end of the wire to prevent the wire from being pulled through the slot. The other end of the wire is provided with a similar head 69. The upward extension 45 of the strap 41 on the lever 35 is normally pulled to the left as seen in Figure 1 so that the lever is releasably held in upward inoperative position. This is done by means of a thermostatic element or fusible link member 70 having one end slipped over an outwardly extending horizontally disposed portion 71 on the lower end of the fixed strap 65 by means of an opening 72 in said end and having its other end slipped over one end of an inverted C-shaped link member 73, through a similar opening 72 at said end. The other end of the link member is connected to the lower end of the wire 68 through an opening or slot 74 in said end of the link member adapted to receive the lower headed end of said wire.

The thermostatic element comprises a pair of complementary plate members 75 arranged side by side in contacting relation, with each plate projecting beyond the other and each being provided with the opening 72 in its projecting end portion. The contacting surfaces or portions of the plates are connected together by fusible metal or material as indicated at 76.

In this form of the invention, the container 1 is positioned in a room or compartment separate and remote from the space to be protected and the thermostatic element is placed in the latter space. When the temperature in the protected space reaches a predetermined degree due to a fire or the like, the fusible material holding the plate members 75 together will melt whereby said plate members will separate and fall apart. When this happens, the resistance against the compression spring 60 will cease and the pressure of the spring will force the lever 35 downwardly against the valve stem 25 thereby forcing the piston valve 21 off of its seat 34 permitting the fluid in the container to escape through the port 6, the delivery pipe 9 and nozzle 13 where it is sprayed on to the fire.

In Figure 4 is illustrated another form of the

invention wherein the container is positioned remote from the space to be protected, as in the form of Figure 1. In this form the pivoted lever 77 has an opening 78 adjacent its outer free end through which the rod 57 passes but here the rod protrudes below the handle member 56 and the compression spring 60 is interposed between the said handle member and the wing nut 61. In this arrangement, the spring exerts a downward pressure on the wing nut thereby exerting a downward pulling action against the lever 77.

The downward pull of spring 60 is resisted by apparatus similar to that shown in the form of Figure 1 but here the headed end of the wire 68 is held by an integral upstanding post 79 formed integrally on the inner end of the lever 77 and having an opening 80 in its upper end through which the wire passes. A similar upstanding post 81 is formed integrally on the extension 18 of the fitting 4 and is provided with an upper slotted end 82 in line with the opening 80 of post 79 for receiving and supporting the end of the horizontal portion of the tubular guide member 48. The lower end of the thermostatic element 70 is connected to the lower protruding end 71 of the fixed strap 65 by a hook member 83 whose shank 84 passes through an opening 85 in said protruding end 71 and extends therebelow. The extending portion of the shank is threaded to receive a wing nut 86 for securing the hook to the end 71 and for taking up the slack in the wire.

When the thermostatic element 70 becomes ruptured and falls apart due to a fire or the like, the resistance to spring 60 ceases and it pulls the lever 77 downwardly thereby moving the valve stem 25 forcing the valve 21 off of its seat whereby the fluid is forced through the delivery pipe 9 and nozzle 13 to the fire.

In the modified form of the invention shown in Figure 5, the entire unit is adapted to be suitably supported in the space to be protected. The apparatus for opening the valve 21 is similar to that of the form of Figure 4 and the fluid is forced directly out through a pipe 9 having a nozzle (not shown) on its end for discharging extinguishing fluid on a fire. The pipe 9 communicates with the chamber 20 in the fitting and communication between the chamber and the central delivery passage 5 is closed by the valve 21.

In this form, the lever 77 is held against valve opening movement by means of the thermostatic element 70 which has one end slipped over the upper reduced portion of the upstanding post 79 on the lever 77 and its other end slipped over the reduced portion of a similar upstanding post 90 formed integrally on the extension 18 of the fitting 4 thereby interlocking the movable lever 77 and the fitting. There is a constant pulling action exerted by the spring 60 on the thermostatic element which facilitates its rupture. As in the form of Figure 4, when the thermostatic element becomes ruptured through rise of temperature, the resistance against the lever 77 will cease and the spring 60 will pull the lever downwardly to open the valve but here the fluid will be forced out through the outlet nut 88 for spraying on the fire.

Figure 6 also illustrates another modified form of unit intended to be positioned in the space to be protected. As here shown, the rod 57 extends above the lever 77 with the spring 60 therearound exerting a downward pressure thereon as in the form of Figure 1. When the valve is moved off its seat by the lever, the fluid is dis-

charged through the pipe 9 as previously described.

The apparatus for holding the lever against valve opening movement comprises a strap member 92 secured to the lever 77 and forming an extension thereof. Another strap member 93 is secured to the fixed handle member 56 and forms an extension of said handle. The latter strap has a portion 94 extending upwardly therefrom to a point above the extending portion of strap 92 on the lever 77. Portion 94 terminates in an inwardly extending portion 95 which is positioned a distance above and which overlaps the outer end of the extending portion 92 on the lever. The thermostatic element 70 is interposed between the overlapping portions with its upper end slipped over the portion 95 of strap 93 and its lower end slipped over the extending end portion of strap 92, thereby interlocking the lever 77 to the fixed handle 56. By this arrangement of parts, the downward thrust of the spring 60 on the lever 77 is imparted to the thermostatic element 70 through which it is transmitted in the form of a pulling action on the end 95 of the strap 93 on the fixed handle, thus facilitating the rupture of the thermostatic element. Upon such rupture, the apparatus operates the same as in the form of Figure 5.

The modified form of the invention shown in Figure 7 is somewhat similar to that shown in Figure 6 but the spring 60 is arranged below the fixed handle 56 as in the forms of Figures 4 and 5 to exert a downwardly pulling action on the lever 77. Here the thermostatic element is interposed between the fixed handle and the movable lever, the lower end of the element being slipped over a strap 96 secured to the lower surface of the handle member and forming an extension thereof and the upper end of said element being slipped over the overlapping protruding end of the strap 92 on the lever. The lever and handle are thus interlocked by the thermostatic element. In this arrangement of spring and element, there is a downward thrust as well as an upward force exerted on the thermostatic element for facilitating its rupture. Upon such rupture of the thermostatic element by high temperature or the like, the operation of the unit is the same as the forms shown in Figures 5 and 6.

Changes in details of construction and arrangement of parts may be resorted to and parts of the invention may be used without other parts without departing from the principle or scope of the invention.

What I claim is:

1. For use with a container adapted to hold fluid under pressure, an outlet fitting adapted to be secured thereto and having a central delivery passage, a chamber formed in the fitting and communicating with said delivery passage, an outlet passage formed in the fitting and communicating with said chamber, a valve movable in the chamber and normally closing communication between the delivery passage and said chamber, means for holding the valve in normal chamber closing position, a spring actuated lever pivotally mounted on said fitting and adapted to engage a portion of said valve for moving the valve to chamber opening position, an upstanding post fixed on said lever, an upstanding post fixed on said fitting and a thermostatic element having one end connected to the post on said lever and its other end connected to the post on said fitting for normally holding said lever against opening movement and for permitting

said movement upon rise of temperature to a predetermined degree.

2. For use with a container adapted to hold fluid under pressure, an outlet fitting adapted to be secured thereto and having a central delivery passage, a chamber formed in the fitting and communicating with said delivery passage, an outlet passage formed in the fitting and communicating with said chamber, a valve movable in the chamber and normally closing communication between the delivery passage and said chamber, means for holding the valve in normal chamber closing position, a spring actuated lever pivotally mounted on said fitting and adapted to engage a fixed portion of said valve for moving the valve to chamber opening position, a handle member formed integrally with said fitting and forming an extension thereof and a thermostatic element interposed between the lever and said handle member for normally holding said lever against opening movement and for permitting said movement upon rise of temperature to a predetermined degree.

3. For use with a container adapted to hold fluid under pressure, an outlet fitting adapted to be secured thereto and having a central delivery passage, a chamber formed in the fitting and communicating with said delivery passage, an outlet passage formed in the fitting and communicating with said chamber, a valve movable in the chamber and normally closing communication between the delivery passage and said chamber, means for holding the valve in normal chamber closing position, a spring actuated lever pivotally mounted on said fitting and adapted to engage a fixed portion of said valve for moving the valve to chamber opening position, a handle member formed integrally with said fitting and forming an extension thereof, a strap secured to said lever and forming an extension thereof, a strap secured to said handle member and forming an extension thereof, said strap extensions being disposed in overlapping relation and a thermostatic element interposed between said lever and said handle member and having one end connected to the extension of the lever and its other end connected to the extension of the handle member for normally holding the lever against opening movement and for permitting said movement upon rise of temperature to a predetermined degree.

4. For use with a container adapted to hold fluid under pressure, an outlet fitting adapted to be secured thereto and having a central delivery passage, a chamber formed in the fitting and communicating with said delivery passage, an outlet passage formed in the fitting and communicating with said chamber, a piston type valve movable in the chamber and normally closing communication between the delivery passage and said chamber, means for holding the piston in normal chamber closing position, a spring pressed lever pivotally mounted on said fitting and adapted to engage a fixed portion of said piston for moving the piston to chamber opening position, a handle member formed integrally with said fitting and forming an extension thereof, a strap secured to said lever and forming an extension thereof, a strap secured to said handle member, said strap extending beyond the free end of said handle member and forming an extension thereof, said strap having a portion extending upwardly to a point above the extension on said lever and having an inwardly extending portion overlapping an extension on

said lever and a thermostatic element having one end connected to the extension on the lever and its other end connected to the overlapping inwardly extending portion of the strap on the handle member for normally holding the lever against opening movement and for permitting said movement upon rise of temperature to a predetermined degree.

5. For use with a container adapted to hold fluid under pressure, an outlet fitting adapted to be secured thereto and having a central delivery passage, a chamber formed in the fitting and communicating with said passage, a valve movable in said chamber and normally closing communication between the passage and the delivery port, means for holding the valve in normal port-closing position, means for actuating said valve into port-opening position, and mechanism for holding the last-named means against port-opening movement, including a flexible member having one end connected to said last-named means, and a heat-responsive device connected to a fixed support and to said flexible member so that said valve will be actuated into port-opening position when said heat-responsive device is subjected to a predetermined degree of heat.

6. A discharge device for a fire extinguisher having a combination carrying handle and valve actuated by moving a control member with respect to the carrying handle comprising a spring, means operatively connecting the spring between the carrying handle and the control member so that the spring normally tends to urge the control member in the discharge position, and thermoresponsive means releasably restraining the movement of the control member under the action of the spring.

7. A discharge device for a fire extinguisher having a combination carrying handle and valve actuated by moving a control member with respect to the carrying handle comprising a coiled spring, a rod extending through the coil of the spring and operatively connected between the carrying handle and the control member so that the spring normally tends to urge the control member in the discharge position, and thermoresponsive means releasably restraining the movement of the control member under the action of the spring.

8. A discharge device for a fire extinguisher having a combination carrying handle and valve actuated by moving a control member with respect to the carrying handle, the carrying handle having an aperture therein, comprising a coiled spring, a rod extending through the aperture in the carrying handle, the rod having an enlarged head so as to prevent it from being withdrawn from the aperture, the rod operatively connected with the control member so that the spring normally tends to urge the control member in the discharge position, and thermoresponsive means releasably restraining the movement of the control member under the action of the spring.

9. A discharge device for a fire extinguisher having a combination carrying handle and valve actuated by moving a control member with respect to the carrying handle comprising, a coiled spring, a rod extending through the coil of the spring and operatively connected between the carrying handle and the control member so that the spring normally tends to urge the control member into the discharge position, a flexible cable, and thermoresponsive means operatively

connected by the flexible cable to oppose the normal action of the spring.

10. A discharge device for a fire extinguisher having a combination carrying handle and valve actuated by moving a control member with respect to the carrying handle comprising, an extension attached to the control member and having openings at each end, a rod extending through the opening at one end and attached to the carrying handle at its other end, a coil spring positioned about the rod and normally tending to urge the control member into the discharge position, a flexible cable having one end extending through the opening at the other end of the extension, and thermoresponsive means connected to the other end of the flexible cable to releasably restrain the discharge of the extinguisher under the action of the spring.

11. A discharge device for a fire extinguisher having a combination carrying handle and valve actuated by moving a control member with respect to the carrying handle comprising a rod adapted to extend through the control member and the carrying handle, a coiled spring positioned about the rod and normally tending to urge the control member into the discharge position, and thermoresponsive means releasably restraining the discharge of the extinguisher under the action of the spring.

12. A combination discharge device, carrying handle and valve for a fire extinguisher comprising a valve body adapted to be secured to the extinguisher, the valve body incorporating a valve, a supporting handle for the valve, a pivotally

mounted control member to actuate the valve, a rod extending between the supporting handle and the control member, a coiled spring positioned about the rod, the control member having an operating surface on one side of its pivotal mounting and an extension on its other side, and thermoresponsive device operatively connected between the extension of the control member and the valve body to releasably restrain movement of the control member under the action of the spring.

13. A discharge device for a fire extinguisher having a combination carrying handle and valve, a control member, the valve actuated by moving the control member with respect to the carrying handle, a rod extending between the control member and the carrying handle, a spring positioned about the rod to tend to urge the control member into the discharge position, and thermoresponsive means directly connected between the control member and the carrying handle to releasably restrain the relative movement of these members under the action of the spring.
